UNITED STATES PATENT OFFICE.

LEON TREFOIS, OF BRUSSELS, BELGIUM.

ROTARY FURNACE GRATE.

1,427,338.

Specification of Letters Patent. Patented Aug. 29, 1922.

Application filed March 4, 1920. Serial No. 363,329.

(GRANTED UNDER THE PROVISIONS OF THE ACT OF MARCH 3, 1921, 41 STAT. L., 1313.)

To all whom it may concern:

Be it known that I, LEON TREFOIS, subject of Belgium, residing at Brussels, Belgium, have invented new and useful Im-
5 provements in Rotary Furnace Grates, (for which I have filed application in Belgium July 13, 1918, Patent No. 273,563; in Germany August 13, 1918, Patent No. 337,741; France, March 22, 1919, Patent No. 497,437; 10 and England, October 14, 1919, Patent No. 153,163), of which the following is a speci-
fication.

This invention has for its object a rotary grate comprising a plurality of con-
15 centric rings turning in opposite directions relatively to each other and provided with regularly spaced slots, covered by auxiliary grates formed by perforated or gridlike bridges, the sides of which arranged towards 20 the direction of motion are open for the discharge of the ashes.

The improved grate is shown by way of example in the accompanying drawing:

Figure 1 is a diagrammatic view in vertical section of the grate; the part at the left hand side assumes the auxiliary grates to be removed, whilst the part on the right hand side shows the concentric grate rings surmounted by auxiliary grates.

30 Figure 2 is a plan view showing all the slots or holes in the grate rings (the auxiliary grates being removed) and the direction of rotation.

Figure 3 shows, to a larger scale, a portion of a grate ring provided with its auxiliary grates.

Figure 4 is a fragmentary vertical section through an auxiliary grate and the main grate.

40 Figure 5 is a partial bottom plan view of the concentric grate rings and discloses the edge of each ring as being provided with a toothed section cooperating with pinions carried on rods which operate from a rotat-
45 ing drive shaft.

The grates are composed of two quite distinct parts, the main grates on the one hand and the auxiliary grates on the other hand. The main grates are formed by a series of 50 concentric rings A, each provided with a discharge incline. The outer grate ring B is provided with a downwardly inclined peripheral flange B' constituting a chute for the discharge of ashes into the lower part

of the body of the hearth of furnace. Each 55 ring turns in the opposite direction to those adjacent to it; the number of rings varies with the size of the apparatus to which the grate is fitted.

All the rings A are provided with discharge slots or holes C. Each hole C is covered by an auxiliary grate E which is perforated or may be of gridlike form and is permanently fixed on the corresponding main grate ring.

60 The main grate rings rotate on ball bearings. The auxiliary grates being fixed to the grate rings accompany the latter in their rotary motion. As the rotation of any ring A considered, always takes place in the same 65 direction, the auxiliary grates are closed at the sides and at the rear, being thus only left open at the front. The walls of the auxiliary grates are made of gridlike or perforated form so as to prevent the per-

70 manent fall of the ashes, whilst leaving the passage free for the air for supporting combustion. This arrangement which reduces the space taken up by an auxiliary grate 75 enables the number of auxiliary grates to 80 be increased and consequently increases the efficiency of the apparatus. When at rest, the ashes thus enter the aperture at the front of the auxiliary grate (see Figure 4) and rest in a heap on the grate rings at their 85 natural slope or angle of repose. But if the rings are turned, the resistance to motion offered by the contents of the producer-
body drives the lower layer into the space 90 in the auxiliary grate. The auxiliary grates 95 thus serve as scrapers and when one of them, by reason of its rotation, has taken the place which its neighbor occupied before the move-
ment, a complete slice or layer of ash has been cut off over the whole surface.

The outer grate ring B likewise discharges its contents down the chute B' by reason of the rotary motion.

100 The central grate ring D, which is also rotary, is freed from the ashes thereon by the effect of the rotary motion. The ashes which lie between the annular spaces served by the auxiliary grates are discharged through the spaces left between the two rings A by the effect of the rotary motion.

105 From these arrangements as a whole it results that the whole surface of the grate is regularly cleaned and regularly supplied

with air for combustion, this air being distributed equally well through the gridlike walls of the auxiliary grates as through the ashes which form the discharge slopes in the auxiliary grates and in the main grate rings.

As shown in Figure 5 the sectors are operated by a mechanism which comprises a hub mounted axially of the grate 10 and a pair of radially disposed shafts b and b' supported in suitable bearings on the hub. The grate rings A and B are provided with toothed sections 10 cooperating with pinions p and p' carried by the shafts b and b' respectively, the said pinions being so arranged that alternate sections 10 are engaged by the pinions of the same shaft. The opposite ends of the shafts b and b' carry worm 15 wheels r and r' respectively, which mesh with worm gears u and u' respectively, mounted on a drive shaft a . By reversing the pitch of the worm wheels r and r' the shafts b and b' may be made to rotate in opposite directions, in which case alternate 20 grate rings will rotate in the same direction and in opposite direction to adjacent rings.

The use of grates with a plurality of concentric zones has for its result the distinctive features and advantages set forth below:

1.—The division of the grate into concentric rings turning in opposite directions relatively to each other, so as to prevent the 35 driving round of the whole mass of fuel in the producer or on the hearth.

2.—The discharge of the ashes by the effect of the rotary motion, these ashes passing along discharge slopes provided between 40 the rings and along the external slope of the grate ring B. It should be remarked that the rotary motion has here only to work on narrow spaces, from which results its efficiency.

3.—The possibility of varying the intensity of the cleaning action from one place to another by varying the speed of one or more of the concentric rings.

On the other hand, the application of 50 grates with slots or divided grates and fixed auxiliary grates produces the following distinctive features and advantages:

1.—The discharge of the ashes through the slots formed in the main grates.

2.—The covering of these slots by the auxiliary grates.

3.—The method of working of the auxiliary grates which act as scrapers and cut a slice or layer from the ashes.

4.—The fact that when an auxiliary grate, by reason of the rotary motion, has occupied the place which its neighbour occupied before the movement, a complete slice of the ashes has been cut over the whole surface.

5. The advantages which result from the

combination of the two systems may be summed up as follows:—

1.—Scientific distribution of the air in the fuel, such as cannot be obtained by any other method:—

(a) Formation of air-passages or holes in the fire due to localized supply of air is rendered impossible, the air passing in at all places at the same time.

(b) Burning of the fuel over a maximum 75 surface permitting uniform, rapid and complete combustion.

2.—Scientific discharge of the ashes obtained by the large number of apertures through which the ashes can pass:—

(a) Uniform removal of the ashes causes 80 perfect regularity of combustion over the whole surface, which may thus be increased without disadvantage, thus enabling apparatus of larger diameter to be constructed.

(b) The uniform removal of the ashes prevents the formation of air passages or holes in the fire due to the presence of ashes in the mass of fuel, a disadvantage which is liable to occur with all other arrangements.

I claim:—

1. A rotary furnace grate comprising a plurality of concentric perforated grate rings, said rings being provided with downwardly projecting means for discharging 95 ashes therefrom, mechanism for rotating adjacent rings in opposite directions relatively to each other, and an auxiliary grate over each perforation in said grate rings and movable with its respective grate ring in a 100 circular path through the under surface of the fire bed, said auxiliary grate comprising a foraminous casing having an end opening which faces the direction of rotation thereof.

2. In a rotary furnace grate, the combination of a plurality of concentrically disposed 105 perforated grate rings having inclined discharge flanges projecting from the under surfaces thereof, means for rotating the adjacent grate rings in opposite directions relatively to each other, and auxiliary grates carried by said rings above said perforations respectively to form circular series of

scrapers movable through paths cut by 110 themselves into the under surface of the fire bed, said auxiliary grates comprising foraminous casings having their ends open which face in the direction of rotation thereof,

whereby material scraped from the under 115 surface of the fire bed will fall into the paths of travel of the open ends of the auxiliary grates and pass through the said opening to the grate rings and thence through the perforations in the latter to the discharge 120 flanges.

3. In a rotary furnace grate, the combination of a plurality of concentrically disposed 125 perforated grate rings, mechanism for rotating the adjacent grate rings in opposite

directions relatively to each, and an auxiliary grate over each perforation and secured to a grate ring, said auxiliary grate comprising a segmental foraminous casing 5 provided with an ash receiving opening in the front end facing the direction of rotation of its respective grate ring.

In testimony whereof I have signed my name to this specification in the presence of two subscribing witnesses.

LÉON TRÉFOIS.
